Henry Mason

UNITED STATES PATENT OFFICE.

HENRY MASON, OF LANCASTER, MASSACHUSETTS.

IMPROVEMENT IN COTTON-PRESSES.

Specification forming part of Letters Patent No. 29,290, dated July 24, 1860.

To all whom it may concern:

Be it known that I, HENRY MASON, of Lancaster, in the county of Worcester and State of Massachusetts, have invented a certain new and useful Improvement in the Press for Pressing Cotton and other Substances; and I do hereby declare that the following is a full, clear, and exact description thereof, reference being had to the accompanying drawings, making part of this specification, in which—

Figure 1 is a plan; Fig. 2, a side elevation, and Fig. 3 an end elevation.

The same letters indicate like parts in all the figures.

The object of my invention is to make a press for pressing cotton which, by direct cog-gearing operated by a constant power applied to a rotating shaft, shall work the platen with a gradually-increasing power proportioned to the gradually-increasing resistance as the cotton or other like article is being compressed; and to this end my said invention consists in combining the platen of the press, when operated by a cogged pinion and cogged rack or the equivalent of these, with the driving-shaft, by whatever power the said shaft may be operated, by means of two increasing and decreasing gears—one on the driving-shaft or the equivalent thereof, and the other on the shaft which communicates motion, directly or indirectly, to the platen—the said increasing and decreasing gears being so formed that the pitch-line of the cogs of the one on the driving-shaft, or the equivalent thereof, gradually approaches the axis, and the pitch-line of the other gradually recedes from the axis, the one gradually increasing in leverage over the other.

In the accompanying drawings, *a* represents the movable platen of a cotton-press, which is to operate against a fixed platen in the usual manner, and which therefore does not require to be represented. The under side of this platen *a* has a bar, *b*, adapted to slide in suitable ways in the frame, and armed on one face with a cogged rack, *c*, so that the platen can be moved up and down by a pinion or cog-wheel, *d*, on a shaft, *e*, which I denominate the "platen-shaft." Parallel with the said plat-

en-shaft *e* is another shaft, *f*, which I term the "driving-shaft," although the driving-power, instead of being applied directly to this shaft, may be applied to another shaft, *g*, which carries a pinion, *h*, that engages a cog-wheel, *i*, on the driving-shaft *f*.

On the platen-shaft *e* there is what I denominate an "increasing-gear," *j*. It is attached to and is to impart motion to the platen-shaft *e*. Its periphery is formed with cogs, and from the first cog at *j* to the last at *j*² each cog is in succession of a greater radius, the increase of radius being regular, and on the driving-shaft *f* there is what I term a "decreasing-gear," *k*, which is precisely the reverse of the increasing-gear *j* on the platen-shaft, so that the first cog, *k*¹, on the decreasing-gear is of the greatest radius, and each in succession of less radius to the last, *k*², which is of the least radius. These two gears mesh into each other, and the increasing-gear *j* on the platen-shaft is driven by the decreasing-gear on the driving-shaft, so that from the time of starting to force up the platen from the position represented in the drawings to the end of the motion of the platen a constant power applied to the driving-shaft will impart to the platen a gradually-increasing power to correspond with the gradually-increasing resistance of the article that is being pressed—such as a bale of cotton—which result I am enabled to attain by a simple gear.

The ratio of increase may be varied at the discretion of the constructor, who can in this way suit the increase to the nature of the article intended to be pressed. The proportions given in the accompanying drawings I deem the best for pressing and baling cotton.

What I claim as my invention, and desire to secure by Letters Patent, is—

Combining the platen-shaft or any equivalent shaft with the driving-shaft or any equivalent shaft by means of increasing and decreasing gears, substantially as and for the purpose specified.

HENRY MASON.
